Des. 807

Stratton & Massey of Philadelphia, Pa.
Assignees of, John F. Allan, of Philadelphia, (opined)
Letters Patent No. 807. Dated June 17th 1856.

The schedule referred to in these Letters Patents, and making part of the same.
To all whom it may concern:

Be it known that I, John F. Allan, of the City of Philadelphia, and State of Pennsylvania, have invented or produced a new and original design for a Cooking Stove, called the "Friedonia," and I do hereby declare that the following is a full, and exact description of the same.

A, is a front view of the Front plates and Fire doors.

B, is a front view of the Back Plate.

C, is a front view of the side Plates illustrating the oven and Fire doors.

A, B, C, illustrates the mouldings and peculiar form (OG) of the front and back.

I claim the general form and proportions, combined with the mouldings, figures and ornaments, substantially as above described.
